UNITED STATES PATENT OFFICE.

PERLEY R. GLASS, OF QUINCY, MASSACHUSETTS, ASSIGNOR TO THE PEER-LESS MACHINERY COMPANY, OF BOSTON, MASSACHUSETTS.

EYELETING-MACHINE.

SPECIFICATION forming part of Letters Patent No. 673,815, dated May 7, 1901.

Application filed December 31, 1900. Serial No. 41,611. (No model.)

To all whom it may concern:

Be it known that I, PERLEY R. GLASS, of Quincy, county of Norfolk, and State of Massachusetts, have invented an Improvement in 5 Eyeletting-Machines, of which the following description, in connection with the accompanying drawings, is a specification, like letters on the drawings representing like parts.

The present invention relates to an eyeletting-machine, and is embodied in a machine in which a number of eyelets are set at one operation, the machine being mainly intended for use in eyeletting shoe-uppers, all of the eyelets along one edge of an upper being set 15 at once.

The present invention relates mainly to novel means for gaging or positioning the material, whereby the two sides of the upper may be consecutively operated upon and the eyelets properly "spread" on each upper—that is to say, the row of eyelets inclined from the edge of the upper toward the front portion thereof.

The invention further relates to certain 25 novel details of construction and arrangement, whereby the operating parts are readily interchangeable, so that the same machine may be used on different classes of work involving variations in the spacing of the eyelets, spread of the eyelets, size of the holes, &c.

The machine embodying the invention is provided with a gang of punches which co-operate with an anvil or support to punch the material, a gang of setting devices corresponding with the gang of punches to set the eyelets in the holes previously punched, and a feed-chute having a gang of raceways to supply eyelets to the several setting devices.

In accordance with the invention the machine is provided with a work-support or table having an opening for the members which punch the holes and set the eyelets and a gage or positioning device for the edge of the upper, which gage is capable of being shifted or oscillated to a predetermined extent, so as properly to position the right and left hand sides of the upper consecutively, the endwise position of each upper being determined by another gage.

50 The punches and setting devices are mount-

ed, respectively, on blocks removable from their supports or carriers, so that if the style of work is to be changed these parts can at once be removed and replaced by others, the anvil and raceways being also interchangeable. 55

Figure 1 is a side elevation, partly in section, of a machine embodying the invention; Fig. 2, a partial front elevation, also partly in section; Fig. 3, a plan view of a portion of the machine to show the support for the material; Fig. 4, a sectional detail showing the removable carrier for the setting devices, and Figs. 5 and 6 details upon a somewhat larger scale to show the action of the gage. 65

The punches *a*, which have tubular cutting portions and annular clenching portions, so as not only to perforate the material, but to co-operate in the eyelet-setting operation, are mounted in an overhanging projection *A*² of the machine-frame *A*, the gang of punches being permanently connected with a block *a*², removably secured to said projection *A*², so that one set of punches can be removed and another substituted without difficulty. 75 As herein shown, Fig. 2, the overhanging projection *A*² is provided with a transverse projection *A*³, adapted to enter a slot *a*³ in the block *a*², which projection determines the longitudinal position of the block, and the said block is locked in place by means of a pin or screw *A*⁴, adapted to be passed through suitable openings in the frame projection and the block *a*².

The anvil or co-operating punching member *b* is removably secured, as by nuts *b*², upon a pair of struts *b*³, pivotally connected at their lower ends with levers *b*⁴, which may be operated in any suitable or usual way, as by eccentrics *b*⁵ on the main shaft *B*. The struts *b*³ are shown as provided with studs *b*⁶, which enter curved slots *b*⁷ in guide-wings *b*⁸, secured to or formed in the frame of the machine, so that as the said struts recede from the punches after the anvil has been forced up against the same the said struts and anvil will be moved laterally to swing out of the way of the setting devices *c*, which then travel upward, each taking an eyelet from one of the raceways *d*² of the eyelet-feed 100

chute d and carrying the said eyelet up toward the material in which the several eyelets are all set at once by the coöperation of the setting devices c with the punches a .

5 The setting devices c are mounted on a supporting-block c^2 , which is removably secured to a carrier c^3 , movable in guides c^4 , said carrier having an operating-lever c^5 , shown as operated by means of the eccentric c^6 . When 10 the style of work is to be changed, the gang of setting devices may be bodily removed and another gang corresponding to the right punches substituted, any convenient kind of fastening devices being employed.

15 As herein shown, Fig. 4, the block c^2 , which forms the immediate support for the setting devices c , is provided with a threaded stem c^7 , adapted to enter a slot c^8 in the carrier c^3 , thus properly centering the block, and the 20 said stem is provided with a tapered nut c^9 , which will engage the walls of the slot and lock the support c^2 in place.

The feed-chute d , which is carried by a reciprocating slide d^0 , is removably connected 25 with said slide, as by nuts d^4 , so that when a change is made in the punches and setting devices the feed-chute can be easily removed and replaced by another. To support and position the material to be operated upon, the 30 machine is provided with a table or work-support e , shown as secured by nuts e^2 upon supports e^3 , the said table being located between the punches and the anvil and setting devices. The material upon said table over- 35 lies an opening e^4 of the proper size and shape to permit the anvil and the setting devices to pass through the same toward the punches, and the said material is properly located by means of a gage.

40 In working on shoe-uppers it is usually customary to set the eyelets so that those at the forward or toe end of the upper are somewhat farther from the edge than those at the rear or ankle end, the eyelets in the finished shoe- 45 upper being spread apart at the toe end of the upper. It is necessary, therefore, when the eyelets are to be set in this way that the two sides of an upper should be gaged differently with relation to the punches and setting devices, and to this end the gage embodying the invention comprises a member pivoted at a point substantially midway between the ends of the rows or gangs of tools and adapted to conform to and extend some

55 distance along the edge of the upper, preferably along so much of said edge as is adjacent to the line of eyelets, the extent of pivotal or oscillating movement being determined by stops f^2 , herein shown as screws or 60 bolts, threaded in lugs f^3 , so as to be readily adjustable to vary the amount of pivotal movement of the gage. In eyeleting one side or member of a shoe-upper, therefore, the operator presses the said upper against 65 the gage, turning said gage in the proper direction until it is arrested by one of the stops f^2 , which will cause the line of eyelets to bear

the proper relation to the edge of the upper. In eyeleting the other member of the upper the operator turns or oscillates the gage in 70 the opposite direction, so that both sides of an upper can be consecutively eyeleted on the same machine.

To determine the proper endwise position of the uppers, the feed-table e is provided 75 with two adjustable gages g , shown as mounted on rods g^2 , held in suitable socket-pieces g^3 by means of set-screws g^4 . The said gages are so arranged as to position the top edge of the shoe-upper, one gage serving for one member of the upper and the other gage serving for the other member thereof.

As shown in Fig. 5, the left-hand member of a shoe-upper (inverted) is shown as in position to be operated upon, the gage f being 85 turned so as to engage the stop f^2 at the right, so that the toe portion of the upper is somewhat farther from the line of punch-holes than the ankle portion thereof. When the other side of the upper is placed in position, 90 as shown in Fig. 6, and the gage oscillated in the opposite direction, the line of holes will bear a similar relation to the edge, the result being that in the finished upper the eyelets are spread at the lower end. It is obviously 95 immaterial how or on what part of the machine the gage is supported, provided that the necessary movement is obtainable to accomplish the purpose described. It might, for example, be practicable to mount the work-support 100 itself on a pivotal support or otherwise provide for a movement thereof to gage the uppers, as described. The machine is also provided with means for adjusting the gage to vary the distance from the edge of the upper 105 at which the eyelets are to be set, the work-support itself being shown as adjustable for this purpose, as by the slots e^5 , through which the upper ends of the supports e^3 extend. By 110 loosening the nuts e^2 the work-support and gage can be moved toward or away from the punches and sets, the opening e^4 being wide enough to admit of such adjustments as may be necessary.

In order to spread the eyelets as described, 115 the line of punches is shown as curved slightly; but if the spread is not desired the punches and sets may be removed and replaced by others arranged in a straight line and the gage anchored or made stationary by a proper adjustment of the gage-stops.

It will be seen from the foregoing description that the specific construction and arrangement of the several instrumentalities may be varied or modified without departing 125 from the invention, and it is not intended to limit the invention to the specific construction shown.

I claim—

1. In an eyeleting-machine, the combination 130 with a gang of punches adapted to punch a number of eyelet-holes at one operation; of a gage conforming to and extending some distance along the edge of the material, said gage

being free to oscillate between stops to vary the angle between the edge of the material and the line of tools, as set forth.

2. In an eyeleting-machine a gang of combined punching and setting devices; a gang of corresponding setting devices to coöperate therewith; a gage for the edge of the material which is free to oscillate on a center substantially midway between the ends of the gangs of tools; and stops to limit the oscillating movement of said gage, substantially as described.

3. In an eyeleting-machine a gang of combined punching and setting devices; a gang of corresponding setting devices to coöperate therewith; a gage for the material which gage is free to oscillate on a center substantially midway between the ends of the gangs of tools; stops to limit the oscillating movement of said gage; and means for adjusting said stops to vary the extent of such movement, as set forth.

4. In an eyeleting-machine, the combination with a gang of tools, each having a punching portion and a setting portion; of a gang of setting-tools to coöperate therewith; a gage shaped to conform to the edge of the material and to extend some distance along the said edge; and means for adjusting the said gage toward and from the lines of tools, as set forth.

5. In an eyeleting-machine, the combination with gangs of tools to punch the material and set eyelets therein, the said gangs of tools being removably secured in the machine so as to be readily interchangeable; of an edge-gage for the material pivotally supported at a point midway between the ends of the gangs of tools; and adjustable stops for said gage whereby the movement thereof may be varied or the gage anchored, substantially as and for the purpose described.

6. In an eyeleting-machine, the combination with a gang of combined punches and setting devices; of a gang of eyelet-setting devices to coöperate therewith; a table or support for the material having an opening whereby the said punches and setting devices can be brought together to operate; and a gage for the material pivotally supported upon said table at a point midway between the ends of the gangs of tools and having adjustable stops

to limit its pivotal movement, substantially as described.

7. In an eyeleting-machine, the combination with a gang of tools for punching a number of holes and setting eyelets therein at one operation of the machine; of an edge-gage having a pivotal support and adjustable stops to limit its pivotal movement; and end gages to determine the longitudinal position of the material, as set forth. 55

8. In an eyeleting-machine, the combination with a gang of tools for punching a number of holes and setting eyelets therein at one operation of the machine; of an edge-gage having a pivotal support midway between the ends of the gangs of tools and adjustable stops to limit its pivotal movement; end gages to determine the longitudinal position of the material; and means for adjusting said end gages, as set forth. 65

9. In an eyeleting-machine, the combination with a gang of stationary punches; of a reciprocating anvil adapted to coöperate therewith in a punching operation; a gang of setting devices adapted to coöperate with the said punches after the punching operation; a stationary feed table or support for the material having an opening for the operation of the several devices; and a gage to position the material upon said feed-table, as set forth. 75

10. In a gang eyeleting-machine for setting eyelets in shoe-uppers, the combination with gangs of tools adapted to punch a number of holes and set eyelets therein at one operation; of a work-support provided with two adjustable gages for the ends of a right and left upper member respectively; a gage for the edge of the upper member along which the eyelets are to be set; said gage being pivotally supported midway between the ends of the gangs 80 of tools; and adjustable stops to limit the pivotal movement of said gage for the edge, as set forth.

In testimony whereof I have signed my name to this specification in the presence of 95 two subscribing witnesses.
